(57) **CLAIM**

I claim the ornamental design for an ISO/DIN SUV stereo mounting device with trim plates, as shown and described.

DESCRIPTION

FIG. 1 is a right front perspective view of an ISO/DIN SUV stereo mounting device with trim plates showing my new design;

FIG. 2 is a top plan view of FIG. 1;

FIG. 3 is a bottom plan view of FIG. 1;

FIG. 4A is a right side elevation view of FIG. 1;

FIG. 4B is a right side elevation in cross-section, along line 4B—4B of FIG. 2, to better illustrate certain features of the disclosed design;

FIG. 5 is a front elevation view of FIG. 1; and,

FIG. 6 is a rear elevation view of FIG. 1.

The appearance of my design for an ISO/DIN SUV stereo mounting device with trim plates, characterized by thin plates around an ISO/DIN SUV stereo head unit, and a pocket. The mounting structure shown in dotted line forms no part of the claimed design.
